O. BREITHAUPT

NAIL CONTAINER AND DISPENSER

Filed March 24, 1927

INVENTOR.

Oscar Breithaupt.

ATTORNEY

UNITED STATES PATENT OFFICE.

OSCAR BREITHAUPT, OF DETROIT, MICHIGAN.

NAIL CONTAINER AND DISPENSER.

Application filed March 24, 1927. Serial No. 177,888.

My invention relates to a new and useful improvement in a nail container and dispenser adapted for use by carpenters and other artisans who are using a large number of 5 nails and find it necessary to replenish the supply at frequent intervals. Carpenters, particularly in shingling, are accustomed to place a number of the nails in the mouth and withdraw the nails as used from the mouth, 10 it having been found that this method of operating is one which permits of rapid work. However, because of various materials used in the manufacture of nails and the treatment of the same, the depositing 15 of the nails in the mouth has become menacing to the health, and it is an object of the present invention to provide a container and dispenser of nails which may be carried by the artisan in a convenient place and from 20 which the nails may be selected, either individually or in such quantities as desired at a time, without slowing up the speed of the operator, as compared with the performance of work when the nails are deposited in the mouth.

Another object of the invention is the provision of a nail container of this class which may be mounted on the clothing and preferably the hat or cap of the wearer, so that 25 the feeding trough is normally held in a horizontal position, and moved to a downwardly inclined position on its feeding end upon a bending of the artisan's body.

Another object of the invention is the provision of a spring-held closure at the 30 end of the trough which serves upon the removal of nails from the trough to agitate the nails remaining in the trough and assist in their projection downwardly through the 35 trough for removal therefrom.

Other objects will appear hereinafter.

The invention consists in the combination and arrangement of parts hereinafter described and claimed.

The invention will be best understood by a reference to the accompanying drawings which form a part of this specification and in which,

Fig. 1 is a perspective view of the invention showing it applied to a cap.

Fig. 2 is a fragmentary sectional view taken on line 2-2 of Fig. 1.

Fig. 3 is a sectional view taken on substantially line 3-3 of Fig. 2.

As shown in the drawings, the invention 55 comprises a receptacle having a rear wall 9, side walls 10 and 11, and a bottom wall 12. The side walls 10 and 11 are each provided with an upwardly directed extension 10' and 11' which serve as guides upon the depositing of the nails therein, the rear wall 9 projecting above these extensions 10' and 11' to provide a flap 13 having openings 14 formed therein, through which may be projected rivets for securing the container to 60 the head piece 15 of the user. As shown in Fig. 2, the bottom 12 is inwardly inclined from each side toward the center where there is formed a slot 16. Secured to and projecting downwardly from the bottom 12 at 65 opposite sides of the slot 16 are guide walls 17 and 18, each of which is provided at the forward end with a forwardly projecting tongue 17' and 18' respectively. Positioned between these guide plates 17 and 18 at their 70 rear end so as to close the space between them is a plate 34. The lower ends 19 and 20 of the guide walls 17 and 18 are angularly turned and each is secured to a plate 21 and 22 respectively which are inclined 75 toward each other to form a trough, the lower edges thereof being separated by the slot 23, these plates 21 and 22 being secured together at the rear end by the clip 24 which 80 serves as a closure for the rear end of the trough, thus formed. Secured to the bottom 12 and projecting inwardly between the guide walls 17 and 18 in a downwardly inclined direction is a guide plate 25. The plates 21 and 22 are secured together at 85 their forward end by the rearwardly projecting tongues 26 and 27 which project from the plate 28 extending above the upper edge of the plates 21 and 22. It will be noted that this plate does not extend to the bottom of the trough thus formed, so that the forward end thereof is not entirely closed.

To provide a closure for the forward end of the trough, I have swingingly mounted on the plate 28 by means of the pin 29, a plate 90

30 having its upper end 31 offset and normally held spaced from the plate 28 by means of the spring 32, the projection of the pin 29 through the plate 30 being a sufficiently loose one to permit the swinging movement described. Secured to the rearward end of the plate 28 and extending inwardly of the trough and inclined upwardly thereof, so as to extend between the 16 tongues 17' and 18' is a guide plate 33 which serves as a closure for the upper side of the forward end of the trough.

In use the device is mounted upon the head gear of the user, and the nails deposited 15 in the receptacle having the bottom 12, these nails, through the agitation which the receptacle will naturally be subjected to while the artisan is performing his duties will be agitated and fall through the slot 16, passing downwardly between the guide plates 17 and 18 and being deflected to the rearward end of the trough by the guide or deflecting plate 25. As shown in Fig. 1, the trough is normally in horizontal position, but the artisan in performing his duties is generally in 20 a position where the head is forwardly inclined, thus moving the trough to inclined position, and permitting the nails which have been deposited in the trough, to extend 25 through the slot 23 and move to the forward end of the trough, the heads of the nails being larger than the slot 23 so that the nails cannot of themselves be removed from the trough. In this way a number of nails 30 will be projected through the slot in the trough and positioned at the forward end thereof at all times while the supply which has been deposited in the receptacle above lasts. These nails may be slid forwardly 35 from the trough, moving the plate 30 to the position shown in dotted lines in Fig. 3. As many nails may be removed at a time as desired, and when the nails are removed from the trough, the closure 30 will snap backwardly into closing position in response to 40 the pressure of the spring 32 thus agitating the nails so that should any of them be in a position whereby their projection through the slot 23 would be prevented, the nails will 45 be jarred to the proper position for projection therethrough.

The device may be made from stamping or other light material so that the container itself will have the minimum of weight, and 50 be of such a size as not to be objectionable when suspended from the headgear of the user.

The end of the trough at which the nails are withdrawn is positioned at the side and 55 well toward the face of the user so that the nails may be as quickly withdrawn from the trough as they can be withdrawn from the mouth. The movement of the artisan therefore, in obtaining the nails from the trough 60 requires no more time than the obtaining of

the nails from the mouth. Furthermore, a larger number of nails may be deposited in the receptacle than may be deposited in the mouth, so that a saving of time is effected by the use of the device.

While I have illustrated and described the preferred form of my invention, I do not wish to limit myself to the precise details of structure shown, but desire to avail myself of such variations and modifications 75 as come within the scope of the appended claims.

Having thus described my invention, what I claim as new and desire to secure by Letters Patent is:

1. A device of the class described comprising: a receptacle having a slot formed in its base; guide plates mounted on said base and depending therefrom in spaced relation to each other, each positioned at opposite sides of said slot; a slot bearing feeding trough carried by said guide plates; a deflecting member positioned between said guide plates and deflecting nails projected through said slot to the rear of said trough; and a spring held closure for the forward end of said trough, the removal of nails from said trough through the forward end of said slot being prevented upon movement of said closure to operative position and being easily 85 accomplished upon movement of said closure to inoperative position.

2. A device of the class described comprising: a receptacle having a slot formed in its base; guide plates projecting downwardly from said base in spaced relation to each other at opposite sides of said slot; a closure for the space between the rear ends of said guide plates; a feeding trough carried by said guide plates, said trough having a longitudinally extending slot formed in its base; a closure for closing the forward end of said trough and preventing movement of nails from the forward end of said slot; a spring for normally retaining said closure in operative position; and a deflecting member mounted between said plates for deflecting said nails upon passage from said slot in said receptacle to the rear of said trough.

3. A device of the class described comprising: a receptacle having a slot formed in its base; guide plates projecting downwardly from said base in spaced relation to each other at opposite sides of said slot; a closure for the space between the rear ends of said guide plates; a feeding trough carried by said guide plates, said trough having a longitudinally extending slot formed in its base; a closure for closing the forward end of said trough and preventing movement of nails from the forward end of said slot; a spring for normally retaining said closure in operative position; a deflecting member mounted between said plates for deflecting 115

said nails upon passage from said slot in said receptacle to the rear of said trough; and a guide member mounted on said trough on its forward end for closing the upper side thereof.

4. A device of the class described, comprising: a receptacle adapted for the reception of nails and having a slot formed in its bottom; a trough carried by and positioned below said receptacle for the reception of

said nails from said slot, said trough having a longitudinally extending slot formed therein; a closure for the forward end of said trough; and an inwardly extending upwardly directed guide member at said end 15 of said trough.

In testimony whereof I have signed the foregoing specification.

OSCAR BREITHAUPt.
